ELECTRICAL CONNECTION

Carl G. Bondeson, Terryville, Conn., assignor to
 National Engineering Corporation, Terryville,
 Conn., a corporation of Connecticut

Application March 13, 1931, Serial No. 522,302

1 Claim. (Cl. 247—1)

This invention relates to electrical connections, and more particularly, to a connection for grounding a conduit and a conductor in an electrical system to a water or other grounding pipe, 5 and in some of its specific aspects it is an improvement on the connection described and claimed in a patent to William E. Eccles, Serial No. 1,914,010, issued June 13, 1933.

In such connections as heretofore provided, a 10 body portion of metal has means for receiving and attaching it to a water or other grounding pipe and to a conduit in the electrical system to be grounded, and usually means is provided on the body to receive a lug attached to a grounding 15 wire carried by said conduit.

A feature of this invention is the provision of a grounding connection in which the lug provided for receiving the grounding wire is made so strong and sturdy that even though it be, as it is in the 20 form of the invention herein illustrated, exposed and liable to be struck by foreign objects when installed, it will effectually resist the blows which it may be expected to receive. By this provision it is unnecessary to sink the lug in a channel 25 for protection, and hence it may be mounted in a position where it is easily accessible and conveniently soldered to the ground wire.

Another feature of this invention is the provision of means on the fixture which supports the 30 lug for holding the latter against turning movement about the axis of the single screw by means of which it is fastened when the screw is being turned to tighten it in place so that the latter operation may be performed by one hand while 35 the other is used for some other purpose.

A further feature is the provision of means whereby the ground wire may be soldered to a terminal which is secured in place by the attaching screw, or alternatively the wire may be securely clamped to the fixture by the action of the attaching screw. This is accomplished by providing on the surface of the fixture on which the lug lies a wire groove leading from the point where the conduit containing the wire is secured 45 to the fixture and continuing around the securing screw spaced therefrom but within the area covered by the lug. Hence, when a solderless connection is satisfactory or permissible, after the grounding wire is merely laid in the groove, 50 the lug is placed over it and then the screw is placed in position and tightened down. This will draw the lug firmly into contact with the ground wire (the groove being shallow enough so that part of the surface of the wire extends beyond the 55 adjacent surface of the fixture) and hold the wire

in good electrical contact with the body of the connection.

Of course, a washer or other suitable plate or block may be used in place of the lug shown, but by having the part which clamps the wire also arranged to have the wire soldered thereto, the one and the same device may be used in its entirety for either a soldered or solderless job.

Other features and advantages will hereinafter appear.

In the accompanying drawing which shows one form of the invention, that at present preferred—

Figure 1 is a side elevation of the ground connection with portions thereof omitted.

Fig. 2 is a plan view of a fixture of the connection.

Fig. 3 is a plan view of the ground connection of this invention showing the same attached to a grounding pipe, a conduit of the electrical system, and the grounding wire soldered in the lug which is attached in place.

Fig. 4 is a longitudinal sectional view of the parts of the connector shown in Fig. 1.

Fig. 5 is a side view of the connection showing one of the fixtures in section with the grounding wire secured in place under the lug.

Fig. 6 is a longitudinal sectional view of the lug to which the wire may be soldered or under which it may be secured.

In the embodiment of the invention shown in the accompanying drawing, the connection comprises two fixtures, a fixture 10 adapted to be connected to a conduit 11 and a fixture 12 adapted to be connected to a ground pipe 13 shown in Figs. 3 and 5. The fixture 12 is substantially the same as the corresponding fixture illustrated in the patent to William E. Eccles, Serial No. 1,914,010, issued June 13, 1933, and comprises two jaw portions 14 and 15 provided with clamping surfaces 95 adapted to securely engage the grounding pipe and form good electrical and mechanical connection therewith. The two jaws 14 and 15 are structurally separate and have ears 18 engaged by clamp screws 19 passing through holes in the 100 ears 18 in the clamping member 14 and into threaded bosses on the clamping member 15.

The fixture 10 which is adapted to be connected to the conduit 11 has a flat portion or table 23 and a cylindrical portion 24, the latter being provided with integral screw threads 26 to receive external screw threads 28 on the conduit 11. The table 23 of the fixture is preferably formed integral with the cylindrical portion 24 and for strengthening purposes webs or fillets 29 may be 110

provided and yet these fillets should not obstruct free access to the end of the flat portion 23 of the fixture.

To permit the fixtures 10 and 12 to be connected to a conduit pipe and a grounding pipe which are angularly disposed, the fixtures are rotatably adjustable relative to each other. For this purpose, in the device to which the present invention is applied, there is provided a cylindrical boss 30 on the clamping member 14 of the fixture 12 and a cylindrical socket 31 on the flat portion or table 23 of the fixture 10. The boss 30 and socket 31 have a comparatively loose fit and are provided for conveniently locating the parts one relative to the other for relative rotary movement preparatory to the securing of the parts together. When the fixtures are located in the desired angular positions relative to each other with the cylindrical boss 30 in the socket 31, a screw 32 is passed through a hole 33 in the table portion 23 of the fixture 10 and enters a threaded hole 34 in the boss 30. Tightening of the screw causes the engaging surface at the base of the boss and the marginal edge of the cylindrical socket to be clamped in intimate contact with each other to thereby prevent rotation of the fixture 10 about the fixture 12.

In this way the conduit pipe 11 is held in firm and good electrical and mechanical contact and connection with the grounding pipe 13.

In grounding electrical systems, it is desired also to not only ground the conduit 11 but also a grounding wire 35 which is carried by the conduit 11.

Heretofore, two methods of securing the end of the ground wire 35 were practiced. In one method the wire was merely wrapped around an attaching screw and such connectors are generally denoted by the term solderless. In other cases the end of the wire was soldered to a tubular lug and the lug secured under an attaching screw. According to the present invention, the device is so arranged that it may optionally be used in either way and with great facility, and hence it is unnecessary for the electrician or jobber to carry two different kinds of ground connections—one for solderless and the other for soldered jobs—effecting a saving and decreasing the capital outlay necessary to carry a proper stock of fittings, besides avoiding the delay and trouble necessary to pick out or obtain the proper fitting for the desired kind of work.

Further, with the lugs heretofore provided it has been found necessary in many instances to provide on the fixture which holds it adequate protection for the lug against blows or other damaging effects from foreign bodies. This has been accomplished by providing a channel in the fixture extending substantially around the lug, and while this method of protection has been adequate the channel walls have impeded free and convenient handling of the wire end and lug in soldering the former in the latter, and in fastening or unfastening the soldered lug.

Accordingly, it is an object of the present invention to provide a lug which is of itself sufficiently strong and rigid to require no protection, that is to say, a self-protecting lug, and further to so arrange the lug and the fixture that either a soldered or solderless job may be performed with equal facility and with the same device. Hence, the lug 37 illustrated herein and shown in section in Fig. 6, is made preferably by casting it of a solid piece of metal of substantial thickness and

size. It has a flat bottom surface 38 and at one end is provided with a hole 39 for receiving the end of the wire 35 and the solder by means of which the wire 35 is electrically and mechanically united to the lug. The other end of the lug is decreased in thickness so as to constitute a flat portion 40 and has a hole 41 through which the attaching screw 32 may pass when being put in place and when, as shown in Fig. 4, the lug is assembled on the fixture 10 the head 32a of the screw engages the flat portion 40 of the lug and firmly holds the lug against the table 23 of the fixture 10.

Heretofore the lugs provided for attaching wires had just sufficient length to provide a portion for engagement with an attaching screw and a socket to receive the wire to be soldered in place. However, in order to protect the ground wire 35 from any damaging blows, the connector lug 37 of the present invention is provided with an extension 41, see Fig. 6, having at least side walls 42 reaching beyond the socket 39 approximately to the end 43 of the threaded cylindrical portion 24 of the fixture. Hence, as shown in Figs. 1, 3 and 4, the wire 35 is protected for its entire length by the conduit 11, cylindrical portion 24, and lug 37.

Of course, it is within the scope of this invention to have the top wall 44 of the lug carried into the extension 41. However, in its preferred form, this is not done—first, because the walls 42 of the lug are adequate to protect the ground wire against blows in all directions, and, secondly, because the opening 45 thus formed permits the lug to be bent as indicated in dot-and-dash lines in Fig. 6, at an angle with respect to the general direction of the wire when soldering the lug to the wire, the wire being bent back into the spaces between the walls 42 after the soldering has been completed.

In order that the device may be used in performing a solderless job without the use of any additional parts and yet have the wire fully protected and securely clamped in good electrical and mechanical connection with the connector, the fixture 10 is provided with a wire groove 46 in the surface of the table 23 beginning at the junction of the table 23 with the cylindrical portion 24 and terminating in an annular groove 47 concentric with the hole 33 through which the attaching screw 32 passes. In using the device, the ground wire 35 is bared and led in the groove 46 and has its end looped so as to fit in the annular groove 47. Then the lug 37 is placed over the wire and the attaching screw 32 is inserted through the holes 41 and 33 in the lug and fixture 10 respectively, and, engaging the threaded hole 34 in the fixture 11, is tightened in place. When this is done, the head 32 of the screw engaging the flat portion 40 of the lug draws the lug tightly down against the ground wire, for the groove 46 and its annular portion 47 are formed in the surface of the table 23 in the area covered by the lug 37. Preferably the groove 46 and its annular portion 47 is made shallow so that the wire 35, shown in Fig. 5, extends above the surface of the table 23 and hence when the screw 32 is tightened the wire is firmly squeezed between the lug 37 and the table portion 23 of the fixture 10. The lug being rigid and strong firmly engages the bared end 35a throughout its entire length and overlying the latter protects it from external blows.

In order to facilitate the application of the lug 37 to the fixture 10, the portion 23 of the latter may and preferably is provided with upstanding nibs 48 between which the enlarged portion of the

lug 47 extends when in proper position. These nibs 48 prevent the lug 37 from turning while the screw 32 is being tightened, thereby permitting the use of one hand of the mechanic for other purposes than for holding the lug while the other is applying the wrench screw-driver to the head 32a of the screw.

The annular portion 47 of the groove 46 in the table 23 may circumscribe the hole 33 in the fixture 10, but it is preferable that it be spaced therefrom by an annular wall 49, see Fig. 2, so as to avoid any possible damage being done to the wire or the loop portion of the wire being unwound as the result of the engagement with the shank of the screw.

Variations and modifications may be made within the scope of this invention and portions of the improvements may be used without others.

Having thus described the invention, what is claimed as new and for which it is desired to obtain Letters Patent, is:—

A grounding connection comprising a body having means for attachment to a conduit pipe containing a grounding wire, and means for attachment to a grounding pipe; and a lug removably mounted on said body and having a socket in which the end of the grounding wire may be inserted to be soldered to the lug, said lug having a surface throughout its length conforming substantially to the portion of the surface of the body underlying it to cover and clamp between itself and the body the end of the grounding wire to make a solderless electrical connection.
